SANITARY APPLIANCE SUCH AS WASH
BASINS, BIDETS, SINKS, BATHS, AND THE
LIKECharles Mallet and Henri Charles Couëtoux,
Paris, France, assignors to Etablissements
Jacob Delafon Compagnie Ceramique de Pou-
illy-sur-Saône et Belvoye, Paris, France, a
company of FranceApplication March 30, 1934, Serial No. 718,138
In France April 6, 1933

11 Claims. (Cl. 4—199)

The object of the present invention is to provide a sanitary appliance such as a wash basin, bidet, sink, bath or the like which fulfills the most rigid requirements of hygiene.

One object of the invention is to ensure the rapid discharge of the polluted water in such an appliance and the consequent removal of the suspended materials.

A further object of the invention is to prevent these suspended materials from fouling in any way the various ducts of the sanitary appliance.

Another object of the invention is to permit all the internal parts and ducts of the appliance to be cleaned easily and completely.

A further object of the invention is to avoid any danger of the mechanical controlling members becoming jammed.

Finally, a still further object of the invention is to avoid the noise which normally accompanies the flow of the water to the waste pipe.

The sanitary appliances which permit the foregoing objects to be attained comprise the features which appear from the following description and from the claims appended to this description.

Sanitary appliances in accordance with the invention are illustrated by way of example in the accompanying drawings, in which:

Figure 1 is a vertical partial section of a wash basin, the section being taken along the axis of the waste duct and of the overflow duct;

Figure 2 is a horizontal section taken along the line 2—2 in Figure 1;

Figure 3 is a partial section of another embodiment of the invention;

Figure 4 is a vertical partial section to a larger scale taken along the line 4—4 in Figure 3;

Figure 5 is a vertical partial section of a bath according to the invention;

Figure 6 is a front view of the lever for operating the rod controlling the valve in the bath shown in Figure 5;

Figure 7 is a vertical partial section to a larger scale taken along the line 7—7 in Figure 5.

The wash basin illustrated in Figures 1 and 2 comprises an emptying duct 2, an overflow duct 8 and a discharge duct 7 extended by the waste pipe 10. All these three ducts 8, 2 and 7 have vertical axes.

The overflow duct 8 which comprises a flow aperture 9 and an upper orifice 10 of substantially equal section to that of the overflow duct 8 has a continuous profile comprising no abrupt bends and no projections, the external generating line *a b* being extended by curves *b c d* connected together and having large radii of curvature.

The rigid rod 16 controlling the waste valve 4 slides in a square orifice 21 in the plug 20 and in the guide 19 of this plug. This guide thus constitutes a vertical guiding axis for the rigid rod 16 which consequently moves vertically parallel to the vertical displacements of the waste valve 4.

This rigid rod 16 has a shape corresponding to that of the curves *b c d* connecting the overflow duct 8 with the emptying duct 2.

A spring 23 secured upon the plug 20 carries 10 a head which engages in the groove 25 of the rod 16 and locks this rod 16 and the valve 4 in the open position.

The plug 20 is held in position by any suitable means for example by a lever 26 provided with a 15 facing 28 which bears upon the inner surface of the overflow duct.

The emptying duct 2, of short length, opens into the base of the porcelain basin 1 and also comprises a profile made up of curves *b' c' d'* 20 having large radii of curvature.

Upon the upper edge of this duct 2 is formed the seating 3 for the valve 4 provided with guiding wings 5.

The emptying duct 2 and the overflow duct 8 25 join each other directly without any intermediate chamber, without any projection and at an acute angle.

Further, the section of the emptying duct 2 is substantially equal to that of the overflow duct 30 at the intersection of these two ducts, thereby again avoiding any projection at this intersection. Consequently, the streams of water follow the ducts 2 and 8 without undergoing any sudden deflection and without forming eddies and they thus 35 reach the discharge duct 7 which is extended by the waste pipe 10.

The three ducts 2, 8 and 7 are of substantially constant section over the whole of their length.

These three ducts 2, 8 and 7 constitute in fact 40 an arrangement having rounded internal forms with no sharp angles with perfectly smooth walls having no projections, free from baffles and with no members for controlling the valve secured upon the walls of the overflow duct or of the 45 discharge duct.

Finally, each of the three ducts 2, 8 and 7 comprises at the opposite end to the junction between these ducts, an orifice 3, 70, 80 having a section substantially equal to the mean section 50 of the said duct.

The combination of these various features possesses a great number of advantages.

In the first place the walls of these ducts 2, 8, 7 55 comprise no points upon which the impurities

suspended in the polluted water can become attached or deposited. Consequently these impurities are carried to the waste pipe 10 and an automatic cleaning assembly is thus obtained. 5 When an additional cleaning becomes advisable from time to time on account of the adherence of impurities to the walls of these ducts, the waste valve 4 and the plug 20 with the rigid rod 16 are removed. The shape given to this rod 16 10 permits this removal to be effected easily and rapidly.

A sponge formed for example by a cloth of suitable size forming a head mounted on the end of a flexible rod will then be inserted in the 15 emptying duct 2. This head will advantageously when out of use have a section equal to the largest section of the three ducts mentioned above, the dimensions of this head being capable of reduction by one-third on account of its 20 elasticity. This sponge thus follows, without difficulty, the three ducts having a continuous profile and which are free from projections and are made up of curves of large radii so that the sponge rubs upon all points of the walls and 25 consequently cleans them perfectly.

The facility of removing and replacing the 30 valve 4 and the whole of its controlling device obviously encourages the user to clean the sanitary appliance frequently and consequently keep 35 it in the greatest state of cleanliness.

In this appliance there is a sure cooperation 35 between the rigid controlling rod and the profile of the ducts which have large radii of curvature for cleaning and maintaining the appliance under the best conditions of hygiene.

Further, the above combination possesses the 40 advantage of distributing the pressure uniformly and consequently of reducing wear to a minimum and distributing this wear uniformly; it 45 removes any risk of jamming of the parts, avoids any choking of the valve by the accumulation of heavy materials and permits these heavy materials to be discharged by virtue of the speed of flow.

Moreover, in the wash basin illustrated in Figure 1, the valve 4 on the emptying duct 2 is advantageously constructed in the following manner:—

The bearing surface 41 of the valve 4 upon the 50 seat 3 does not extend to the upper edge of the cone formed by this seat 3 thereby avoiding any damage and scratching of the layer of enamel 55 which covers the ceramic body of the appliance.

Further, the valve 4 is extended by a part 42 55 forming a cap having a diameter D greater than the larger diameter d of the cone forming the seat 3, so as to cover the upper end of this cone and facilitate handling the valve 4 if the latter 60 is replaced in position before the controlling mechanism 15 has been mounted in place. Here again, this arrangement co-operates in facilitating dismounting and cleaning.

Finally, in the wash basin illustrated in Figure 1, a closing member such as the plate 31 is mounted upon a stem 30 itself secured upon the controlling rod 16 of the waste valve 4. This plate 31 covers the flow aperture 9 which connects the overflow duct 8 with the basin 1, when the knob 22 is drawn upwards, that is to say, when the valve 4 is raised and the water in the basin flows through the waste pipe 10. This closure of the flow aperture 9 prevents the occurrence of the noise and gurgling which tend 75

to be produced when water flows out of the basin 1.

In the embodiment illustrated in Figure 3, the rigid control rod 16 co-operates in guiding the waste valve 4, thereby further removing any danger of jamming. For this purpose, the control rod 16 is formed of two parts 16¹, 16² mounted adjustably relative to one another, for example, by means of a device comprising a screw threaded rod 53, a nut 51 and a lock-nut 10 52. Further, the part 16¹ of the control rod 16 comprises at 54 a guide for the end 53 of the waste valve 4.

This arrangement possesses various advantages. 15

In the first place, on account of the fact that the valve 4 is guided at 54 by means of its tail 53, no guiding wings are required on this valve, thereby avoiding any wear of the waste duct 2. This advantage is of particular interest when 20 the valve 4 is mounted directly in a waste duct 2 formed in the material of the basin itself without the interposition of any bond or metal sleeve, in which case it is consequently desirable to avoid any friction upon this material. 25

Further, the adjustability of the position of the two parts 16¹, 16² relative to one another, permits the position of the guiding end 54 to be regulated so that this end is always directly below the tail 53 of the valve 4 in spite of any irregularities which may occur in the casting and manufacture of the body of the wash basin.

The wash basin illustrated in Figure 3 also comprises a seat of special construction for the waste valve. This seat is formed by a metal ring 3 35 connected to the body of the wash basin 1 by screws 140 which screw into the seat and bear by means of their heads upon the external surface of this body 1, thereby providing a secure attachment of the ring upon the body. 40

This metal ring presses upon a shoulder 143 in the body 1 of the wash basin, with the interposition of a washer 144 having a U-shaped cross section and made for example of malleable lead. This washer is squeezed into the interior of the 45 emptying duct 2 and the excess metal is then removed in order to permit an emptying duct 2 to be obtained having a perfectly smooth inner surface which comprises no projections capable of retaining the impurities suspended in the polluted water. 50

The free space 142 formed between the ring 3 and the body 1 is filled with a cement.

In this way, the seat is securely mounted, a good fluid-tight joint is provided and an empty- 55 ing duct having a perfectly smooth inner surface is obtained.

In the embodiment illustrated in Figures 5 to 7, the sanitary appliance is a bath.

The overflow duct 108 enters the body 101 of 60 the bath laterally at 170 through an orifice which itself forms the flow orifice. A ring 78 connected to this body 101 by sealing studs 79 comprises a neck 76.

The cap 120 forming a plug is connected in an 65 easily removable manner, for example by a bayonet joint 86 to the attachment neck 76.

An operating lever 122 turns freely in the removable plug 120. By means of an eccentric 100 it controls the operating rod 116 which lifts the 70 waste valve 104, this rod having a profile which greatly facilitates mounting it in the overflow duct 108 and also its dismounting.

The stem 81 of the operating lever 122 comprises a closure forming extension 131 which is 75

adapted to close the flow aperture 109, thereby avoiding the noise which usually accompanies the flow of water through to the waste pipe 110.

The bath illustrated in Figures 5 to 7 comprises a valve seat constructed in the following manner:—

A metal ring 3 is again secured to the body of the basin by screws 140 as already explained with reference to Figure 4. This metal ring presses 10 upon a packing 145 made of malleable metal for example of lead, and this packing 145 contracts slightly under the pressure exerted by this ring.

The excess material projecting into the emptying duct is removed so as to give this duct a perfectly smooth surface.

The free space 142 formed between the ring 3 and the packing 145 is filled with a cement.

In this way, the technical advantages already described with reference to the example illustrated in Figures 3 and 4 are obtained.

What we claim is:—

1. In a sanitary appliance such as a wash basin, a wash basin body having a basin, an emptying duct, an overflow duct and a discharge duct, these three ducts having from their inlet to their outlet openings a constant section and smooth walls, the overflow duct being connected to the emptying duct by curves of large radius, a valve having a vertical axis mounted in the emptying duct and controlling the orifice of the said duct, a guiding member having a vertical axis movably mounted in the overflow duct, a rigid rod, guided by the guiding member, engaging in the overflow duct and actuating the valve, this rigid rod having a shape corresponding to that of the curves, connecting the overflow duct with the emptying duct.

2. In a sanitary appliance such as a wash basin, a wash basin body made of a material such as ceramic material, this body comprising a basin, an emptying duct opening into the basin by a conical part forming a seat, this wash basin body also comprising an overflow duct and a discharge duct, these three ducts having from their inlet to their outlet openings a constant section and smooth walls, the overflow duct being connected to the emptying duct by curves of large radius, a layer of enamel covering the surface of the basin, a valve having a vertical axis mounted in the emptying duct, this valve comprising a bearing surface of smaller height than the height of the seat, controlling means carried by the wash basin body and adapted to actuate the waste valve.

3. In a sanitary appliance such as a wash basin, a wash basin body having a basin, an emptying duct and a seat, an overflow duct and a discharge duct, these three ducts having from their inlet to their outlet openings a constant section and smooth walls, the overflow duct being connected to the emptying duct by curves of large radius, a valve having a vertical axis bearing upon the seat of the emptying duct and comprising an extension having a cap of larger diameter than the diameter of the seat of the emptying duct and overlapping this seat above the plane of the basin controlling means carried by the wash basin body and adapted to actuate the waste valve.

4. In a sanitary appliance such as a wash basin, a wash basin body having a basin, an emptying duct, an overflow duct and a discharge duct, these three ducts having from their inlet to their outlet openings a constant section and smooth walls, the overflow duct being connected

to the emptying duct by curves of large radius, a seat provided at the upper part of the emptying duct and composed of a metal ring, screws connecting this ring to the body of the wash basin and a cement packing filling the joint between this ring and the said body, a valve having a vertical axis mounted in the emptying duct and bearing upon the said seat; controlling means carried by the wash basin body and adapted to actuate the waste valve.

5. In a sanitary appliance such as a wash basin, a wash basin body having a basin, an emptying duct, an overflow duct and a discharge duct, these three ducts having from their inlet to their outlet openings a constant section and smooth walls, the overflow duct being connected to the emptying duct by curves of large radius; a seat provided at the upper part of the emptying duct and composed of a metal ring; screws connecting this ring to the body of the wash basin; a washer made of malleable metal and having a U-shaped cross-section pressed by the metal ring upon the body of the wash basin; a cement packing filling the joint between this ring and the said body; a valve having a vertical axis mounted in the emptying duct and resting upon the said seat; controlling means carried by the body of the wash basin and actuating the waste valve.

6. In a sanitary appliance such as a wash basin, a wash basin body having a basin, an emptying duct, an overflow duct and a discharge duct, these three ducts having from their inlet to their outlet openings a constant section and smooth walls, the overflow duct being connected to the emptying duct by curves of large radius; a seat provided at the upper part of the emptying duct and composed of a metal ring; screws connecting this ring to the body of the wash basin, a packing made of malleable metal being pressed by its external surface by the metal ring and being deformed under this pressure; a cement packing filling the joint between this ring and the said body; a valve having a vertical axis mounted in the emptying duct and bearing upon the said seat; controlling means carried by the body of the wash basin and adapted to actuate the waste valve.

7. In a sanitary appliance such as a wash basin, a wash basin body having a basin, an emptying duct, an overflow duct and a discharge duct, these three ducts having from their inlet to their outlet openings a constant section and smooth walls, the overflow duct being connected to the emptying duct by curves of large radius; a valve having a vertical axis mounted in the emptying duct, this valve comprising an actuating tail situated below the valve and on a vertical axis; a guiding member having a vertical axis removably mounted in the overflow duct; a rigid rod guided by the guiding member engaging in the overflow duct; a supporting and centering member carried by the rigid rod and engaging over the tail of the valve in order to actuate the latter.

8. In a sanitary appliance such as a wash basin, a wash basin body having a basin, an emptying duct, an overflow duct and a discharge duct, these three ducts having from their inlet to their outlet openings a constant section and smooth walls, the overflow duct being connected to the emptying duct by curves of large radius; a valve having a vertical axis mounted in the emptying duct, this valve comprising an actuating tail situated below the valve and on a vertical axis.

cal axis; a guiding member having a vertical axis removably mounted in the overflow duct; a rigid rod guided by the guiding member, engaging in the overflow duct; an adjustable member mounted upon the rigid rod; a supporting and centering member carried by the adjustable member, this supporting member engaging over the tail of the valve in order to actuate the latter.

9. In a sanitary appliance such as a wash basin, a wash basin body having a basin, an emptying duct, an overflow duct, a flow aperture and a discharge duct, these three ducts having from their inlet to their outlet openings a constant section and smooth walls, the overflow duct being connected to the emptying duct by curves of large radius; a valve having a vertical axis mounted in the emptying duct controlling the orifice of the said duct; controlling means carried by the wash basin body and adapted to actuate the waste valve; a closure member movable parallel to the axis of the overflow duct, mounted upon the controlling means and controlling the flow aperture of the overflow duct.

10. In a sanitary appliance such as a wash basin, wash basin body having a basin, an emptying duct, an overflow duct opening directly into the basin and a discharge duct, these three ducts having from their inlet to their outlet openings a constant section and smooth walls, the

overflow duct being connected to the emptying duct by curves of large radius; a valve having a vertical axis mounted in the emptying duct and controlling the orifice of the said duct; a removable plug having a flow aperture mounted in the mouth of the overflow duct; an operating lever rotatable in this plug; controlling means actuated by the operating lever, engaging in the overflow duct and adapted to actuate the waste valve; a closure member carried by the operating lever and controlling the flow aperture upon the rotation of the said operating lever.

11. In a sanitary appliance such as a wash basin, a wash basin body having a basin, an emptying duct, an overflow duct and a discharge duct, said three ducts having from their inlet to their outlet openings a constant section and smooth walls, the overflow duct being connected with the emptying duct by curves of large radius, a valve having a vertical axis mounted in the emptying duct and controlling the orifice thereof, a guiding member movably mounted in the overflow duct, a rigid rod guided by the guiding member engaging in the overflow duct and actuating said valve, said rod having a shape corresponding to that of the curves connecting the overflow duct with the emptying duct.

CHARLES MALLET.

HENRI CHARLES COUËTOUX.
